UNITED STATES PATENT OFFICE.

LEROY M. LEWIS, OF MERION, PENNSYLVANIA.

DRY-PIPE VALVE.

Application filed April 11, 1922. Serial No. 551,599.

My invention relates to dry pipe valves for use in automatic sprinkler systems and which comprise a casing and an air valve and a water valve within the casing so arranged that air pressure exerted on the former is operative to maintain the latter in closed position against the pressure of the water in the supply pipe, a valve of this general character forming the subject of my 10 copending application for U. S. Letters Patent Serial No. 514,440 filed November 12, 1921.

A principal object of the present invention is the provision of means for automatically opening and closing a drain from one of the chambers of the valve in correspondence with the position of the water valve clapper and in association with means for preventing the water valve clapper from accidentally closing after it has opened, so that under no circumstances can the flow of water through the dry pipe valve be interrupted after it has been once initiated. A further object of my invention is to provide 20 means in association with the drainage valve and manually operable from the outside of the dry pipe valve casing through the medium of which the means which are effective to prevent the accidental closure of the water valve as aforesaid may be actuated during the operation of resetting the dry pipe valve to permit the water valve to be returned to its seat.

A further object of my invention is the 30 provision of means operative to open a drain from the interior of the dry pipe valve when the water valve clapper is brought to closed position and to maintain the drain open so long as the water clapper remains in such position and which, when the water clapper moves from its seat and permits the entrance of water into the interior of the casing, are operative to automatically close the drain to prevent the escape of water therethrough so long as the water clapper remains in open position.

A still further object of my invention is to generally improve and simplify the construction of dry pipe valves so as to reduce their cost and facilitate the process of manufacture; to so dispose and arrange the various parts as to reduce the size and bulk of the valve casing and to effect such other various objects, improvements and novel features of construction and arrangement as are hereinafter more specifically referred

to or described or are apparent from the accompanying drawings forming a part hereof.

In the said drawings I have illustrated a dry pipe valve embodying a preferred form of my invention, Fig. 1 being a vertical section through the valve with certain of the parts in elevation, the air and water valve clappers being shown in full lines in normal or closed position and their position when fully open being indicated in dotted lines. Fig. 2 is a fragmentary enlarged top plan view of the drain operating mechanism and adjacent parts, a portion of the water valve clapper being shown in plan and a portion of the casing in horizontal section. Fig. 3 is an enlarged fragmentary vertical section on the line 3—3 in Fig. 2 looking in the direction of the arrows but showing the water valve clapper in partially open position and the drain operating mechanism in closed position, and Fig. 4 is a fragmentary detail top plan view of the drain valve and certain associated parts, a portion of the dry valve casing being shown in horizontal section. Like numerals are used to designate the same parts in the several figures.

Referring now more particularly to the drawing, the dry pipe valve shown therein comprises a main casing 1 provided with an inlet 2 which, when the valve is in use, is connected to a suitable water supply pipe while above and in substantial vertical alignment with the inlet, the casing is provided with an outlet 3 which in use is connected to a distributing pipe. The casing may be considered as divided into upper and lower chambers 5 and 6 through the medium of a web formed integrally with the casing, the upper chamber being provided with a connection 7 positioned in its wall at substantially the height at which this chamber is kept filled with priming water under normal conditions of operation. Through this connection both the priming water and the air for filling the system may be conveniently introduced from suitable sources of supply. The chamber 6 is provided with a connection 8 from which a pipe may be extended to the alarm valve usual in sprinkler systems, while the inlet may also be provided with a connection 9 for convenient attachment of a suitable valve for testing the presence or absence of water in the supply pipe and inlet.

Supported by the web 10, which substan-

tially separates the upper and lower chambers, is an air valve seat 12 conveniently consisting of a ring of babbitt metal, the web being angularly disposed in the casing and bored out at its center within the seat 12 in such manner as to afford a clear passage from the inlet 2 to the outlet 3, the angle of inclination of the web and face of the seat in the particular valve illustrated being substantially 45° to the horizontal.

The valve clapper of the air valve comprises a substantially disk shaped member 15 with a flexible annular gasket 17 of rubber or other suitable material disposed at its periphery and clamped in position by a suitable ring 19 held by screws 20 or in any other convenient manner, the arrangement being such that the gasket is operative to engage the upper face of the seat 12 and form a tight closure when forced thereagainst. The valve clapper is carried by a suitable arm or arms 22 conveniently formed integral with the clapper, curving outwardly and downwardly from its periphery and pivoted at the outer end on a transversely extending, horizontally disposed pivot shaft 24 having its ends secured in the casing wall in any suitable or convenient manner, the arm and clapper being thus free to revolve about the axis of the shaft as the former is moved toward or away from its seat.

For closing the inlet 2 a suitable water valve clapper 25 of any convenient or desired form is employed. As shown, the clapper comprises a substantially circular metallic disk adapted to engage the upper face of an annular seat 26 threaded into the wall of the casing adjacent the mouth of the inlet 2 and disposed in a horizontal plane. The water clapper is provided with one or more outwardly extending arms 27 preferably integral with the clapper and pivoted at their outer ends on a transversely extending horizontally disposed pivot shaft 28 the ends of which are secured in the casing in any convenient way, the relative position of the shafts 24 and 28 being such that when the two clappers are moved from normal or closed position, in which they are disposed in a relatively angular relation, to full open position (as indicated in dotted lines in Fig. 1), they will approximate a substantially parallel relation.

Means are also provided for connecting the water valve clapper with the air valve clapper in such manner as to enable the same to work in unison. Conveniently for this purpose the water valve clapper is provided with a pair of centrally disposed, laterally spaced, upwardly projecting ears 33 between which one end of a link 34 is pivoted on a horizontal pivot pin 35, the other end of the link being pivoted on a horizontal pivot pin 37 between a pair of downwardly directed, laterally spaced ears 38 formed integral

with the water valve clapper substantially adjacent its center, the ends of the link and the adjacent ears being bored for the passage of the pivot pins which are held in position in any convenient way as by cotter pins 39. It will be noted that as the pivot 28 is located between the pivots 24 and 35 any tendency of the valve clapper to move laterally across the face of its seat when the air clapper is brought to fully seated position and which might otherwise occur owing to the angular thrust of the link 34 is thus entirely negated.

In the preferred construction substantially the whole of that side of the casing toward which the air clapper turns in its opening movement is left open when the casing is cast, and a cap or cover 43 of suitable form is provided for operatively closing the same, said cover being removably held in position by suitably disposed bolts 44 and preferably provided on its inner face with a resilient stop 45 of rubber or other suitable material positioned to limit the movement of the air valve clapper, the position of the stop being such as to permit the clapper to cross the vertical toward the end of its opening movement so that once the limit thereof is attained the weight of the several parts becomes operative to maintain the clappers in open position until the air valve is manually returned to its seat, which operation may be effected after removal of the cover.

For the purpose of draining the lower chamber 6 of any water which may seep into the same when the water valve is closed, and for automatically closing the drain whenever the water valve is open, I provide suitable means now to be described and preferably associate the same with means for preventing an accidental closure of the water valve clapper after it has once opened, the useful function performed by said latter means being to positively prevent the clapper from re-seating itself should the air clapper rebound from the resilient stop following a very violent upthrow of the clappers or should the force of the water in the supply pipe be insufficient to throw the clappers past the vertical on an opening movement thereof. Additionally, I preferably so arrange portions of the drain mechanism as to permit the manual actuation from the exterior of the casing of the means for preventing the closure of the water valve clapper so that in the operation of resetting the valve said last mentioned means may be manually removed from the path of the water valve clapper to permit its return to its seat.

For effecting the functions just described, I preferably dispose certain means in a sort of pocket formed in the casing adjacent the chamber 6 and on the opposite side of the

inlet from the pivot 28, this pocket which may conveniently be designated as the drain chamber 6' being in free communication with lower chamber 6. Said drain chamber 6' is conveniently formed by extending the side wall of the casing outwardly adjacent the inlet as at 1' so that at this point a horizontal section of the casing exhibits a substantially circular form as best shown in Fig. 2, the bottom of the drain chamber being initially open and adapted to be operatively closed by a removable plate or plug 50 held in position by bolts 51 and provided with a vertical, internally threaded bore into which is screwed a hollow bushing 52 conveniently provided with an exterior flange 53 which abuts a shoulder formed in the plate to limit the distance which the bushing can be screwed therein and to form a tight closure. The bushing is sufficiently long to extend into the chamber 6' above the upper face of the plate and the wall of its projecting end is pierced by one or more ports 55. Below the ports the interior of the bushing is constricted and provided with a suitable, preferably conical, seat 56 adapted to co-operate with a suitable conical surface 57 on a valve poppet 58 disposed within the bushing. This poppet below its conical portion is provided with an elongated stem 59 of sufficient length to project below the lower end of the bushing, while above its said conical surface for a suitable distance the poppet is preferably of cylindrical cross section 85 of a diameter to form a loose working fit in the cylindrical upper end of the bushing, the arrangement being such that when the poppet is lifted from the seat a free drain passage is afforded through the ports 55 to the lower end of the bushing through which water accumulated in the casing may be vented therefrom.

The upper extremity of the cylindrical portion of the poppet is preferably milled off on opposite sides so as to provide a tongue 60 which extends between a pair of laterally spaced ears 61 formed on a trip lever 62 pivoted on a horizontally positioned pin 63 supported in a pair of upwardly curved arms 65 preferably formed integral with the plate 50 and spaced on opposite sides of the bushing 52, the axis of the pin being disposed between the axis of the poppet and the water valve clapper. The tongue 60 of the poppet is pivotally supported between the ears 61 of the lever by a pivot pin 67 extending between the latter and through a hole in the tongue, while the trip lever is provided with a toe 68 extending 110 toward the water valve clapper, the toe and ears 61 extending in substantially opposite directions with respect to the pivot 63. The water valve clapper comprises a preferably integral lip 69 extending radially outward in the direction of the toe 68 and so disposed

that when the clapper is closed on its seat the lower part of the lip will engage the toe and depress the same to substantially horizontal position as shown in Fig. 1 thereby lifting the poppet from the seat 56 and opening the passage through the bushing. As the weight of the ears and poppet on one side of the pivot 63 is considerably in excess of that of the toe on the other side thereof, the poppet tends to return to its seat by 125 gravity as the water valve clapper moves upwardly so that with a relatively small opening movement of the latter the poppet drops to engagement with its seat and closes the drain passage from the casing.

For preventing the automatic return of the water valve clapper to its seat after it is moved therefrom for a predetermined distance, I dispose a dog 70 substantially above the poppet and pivot the same upon a horizontally disposed transversely extending pivot 72 the ends of which are extended into suitably disposed bosses 73 on the interior of the casing, screw plugs 74 threaded into the ends of the bores in the casing walls through which the pivot is inserted serving to retain the latter in position as shown in Fig. 2. This dog is provided with a toe 75 extending toward and intercepting the path of movement of the lip 69 on the valve clapper. The upper outer face of the lip is under-cut in such manner as to be capable of engaging the upper surface of the toe of the dog as best shown in Fig. 3, and the dog is so formed that a portion thereof on the opposite side of the pivot 72 will engage a suitably disposed lug 77 on the interior of the casing when the toe is depressed to thereby limit downward movement of the toe, the parts being so arranged, as will be evident from an inspection of Figs. 1 and 3, that when the water valve clapper is swung upwardly from normal position the lip 69 will lift the dog out of its path but the moment that the lip passes the toe, the dog will drop back by gravity into the path of the lip, so that on a reverse or closing movement of the clapper the toe will engage beneath the lip and prevent the clapper from returning to its seat. In order to guard against the dog being thrown past the vertical on the opening movement of the clapper to assume a position from which it would not drop back into the path of the lip, the dog is provided with a stop 79 disposed so as to strike against the casing.

For effecting manual operation of the dog by movement of the poppet 58, I provide the dog with a pair of downwardly directed, laterally spaced lugs 82 which extend below the pivot 72 in vertical alignment with the ends of the pivot 67 which are extended outwardly beyond the outer faces of the ears 61 in such manner that when the poppet is lifted the ends of the pivot will engage the

under surface of the lugs 82 and raise the toe of the dog, the point of contact between the lugs and pivot being in a plane lying between the toe of the dog and the pivot 72.

5 It is believed in view of the foregoing description of the form and arrangement of the several elements of the dry pipe valve in their preferred embodiment, that a detailed description of the operation of the valve is unnecessary, as it will be readily understood that when the air and water clappers are in closed or normal position, the poppet 58 is raised so as to open the drain from the lower chamber, and the toe of the dog supported on the upper surface of the lip 69. Upon the opening of the clappers the dog is thrown upwardly out of the path of the lip but immediately returns to a position to intercept its path and prior to the time when the water valve could re-seat itself by reason of a rebound or of insufficient water pressure, while as soon as the pressure on the toe 68 is relieved by the upward movement of the clapper, the poppet seats itself in the bushing to prevent the escape of water from the casing so long as the clapper remains in open position. When it is desired to reset the valve the cover 43 is removed and the dog lifted out of the path of the lip by manually raising the stem of the poppet from the outside of the casing, after which the valves may be closed down on their seats, and the cover replaced.

20 While I have herein described and illustrated with considerable particularity a preferred embodiment of my invention, I do not thereby desire or intend to limit myself to any precise details of construction or arrangement of parts as the same may be modified and varied from the particular form and arrangement to which I have referred, without departing from the spirit and scope of the invention as defined in the appended claims.

25 Having thus described my invention, I claim and desire to protect by Letters Patent of the United States:

30 1. A dry pipe valve comprising a casing having a chamber, a water inlet communicating with said chamber, a hinged valve clapper controlling said inlet, a drain valve communicating with said chamber and having a vertically movable poppet, a trip member extending into the path of movement of said clapper and movable thereby, a dog horizontally pivoted above the poppet and also extending into the path of movement of said clapper, adapted to be positively moved by the clapper in one direction and operative to limit the movement of the clapper in the other direction, and means connecting said trip and said poppet and adapted to contact said dog whereby said dog may be moved out of the path of said valve clapper by lifting the poppet.

35 2. A dry pipe valve comprising a casing having a chamber, a water inlet communicating with said chamber, a hinged valve clapper controlling the inlet, a drain valve communicating with said chamber and comprising a hollow bushing forming a valve seat, a poppet vertically movable in said bushing and cooperative with said seat, a horizontally pivoted trip member extending into the path of movement of said clapper and pivotally connected with said poppet by a horizontally disposed pivot pin, and a dog pivoted in the casing and having a portion extending into the path of said clapper and a lug adapted for engagement by said pin, whereby the position of said dog may be altered by vertical movement of said poppet.

40 3. A dry pipe valve comprising a casing having a chamber, a water inlet communicating with said chamber, a hinged valve clapper controlling the inlet, a drain valve communicating with said chamber and comprising a hollow bushing forming a valve seat, a poppet vertically movable in said bushing and cooperative with said seat, a horizontally pivoted trip member extending into the path of movement of said clapper and pivotally connected with said poppet by a horizontally disposed pivot pin, and a dog horizontally pivoted in said casing and having a toe on one side of the pivot adapted to extend above the clapper when in closed position, a portion on the other side of said pivot adapted to contact the casing to limit the movement of the dog in one direction and a lug positioned for engagement by said pin whereby the position of said dog may be altered by a vertical movement of said poppet.

45 4. A dry pipe valve comprising a casing having a chamber, a water inlet communicating with the chamber, a hinged valve clapper controlling said inlet, a drain valve for said chamber comprising a poppet having a stem projecting outside of the casing and vertically movable with respect thereto, a dog horizontally pivoted in the casing substantially above said poppet and having a toe extending into the path of movement and projecting above a portion of said clapper when the latter is in closed position and means cooperative with the casing to limit the extent of downward pivotal movement of said toe when said clapper is in open position, and means movable with said poppet and adapted to engage the dog whereby the position of the dog may be altered from the outside of the casing by movement of said stem.

50 5. A dry pipe valve comprising a casing having a chamber, a water inlet communicating with said chamber, a hinged water clapper controlling said inlet, a drain valve for said chamber comprising a vertically movable poppet having a stem extending outside

of the casing, trip means in association with said poppet whereby when said clapper is in position to close said inlet the poppet will be raised and when in position to open said 5 inlet the poppet will be lowered, a dog pivoted on a horizontal pivot within the casing having a toe extending into the path of movement of said clapper adapted for actuation by the clapper when moving from 10 closed to open position and means cooperative with the wall of the casing to limit the extent of downward movement of said toe about said pivot in either direction, and means connecting said trip means and said 15 poppet adapted to engage the dog when said poppet is raised whereby the toe of the dog may be lifted out of the path of the clapper by moving the end of the stem projecting from the casing.

20 6. A dry pipe valve comprising a casing having a chamber, a water inlet communicating therewith, a pivoted valve clapper adapted to open and close said inlet, a dog horizontally pivoted in the casing 25 and having a toe adapted to extend above

and into the path of movement of the clapper for positive actuation by the clapper during its opening movement, and means whereby a vertical movement may be manually imparted to the dog from the exterior 30 of the casing to move the dog out of the path of the clapper.

7. A dry pipe valve comprising a casing having a chamber, a water inlet communicating therewith, a pivoted valve clapper 35 adapted to open and close the inlet, a dog pivoted in the chamber and having a toe adapted to be raised by the clapper during its opening movement, means for maintaining the toe of the dog in a position to limit 40 a downward movement of the clapper toward its seat after the clapper has opened, and a drain valve for said casing including a member partially extending outside of the 45 casing and adapted when manually actuated to move said dog from said position and out of the path of said clapper.

In witness whereof, I have hereunto set my hand this 10th day of April, 1922.

LEROY M. LEWIS.
